UNITED STATES PATENT OFFICE.

CLAUDE ASTOLFO CONOVER, OF NEWBURGH, NEW YORK.

DETACHABLE TOOTH.

1,351,623.

Specification of Letters Patent. Patented Aug. 31, 1920.

Application filed January 8, 1920. Serial No. 350,079.

To all whom it may concern:

Be it known that I, CLAUDE A. CONOVER, a citizen of the United States, and a resident of Newburgh, in the county of Orange and State of New York, have invented a new and useful Detachable Tooth, of which the following is a full, clear, and exact description.

This invention relates to dental work and particularly to an improved removable tooth, and has for an object to provide a construction which will be mechanically effective for the purpose desired, and at the same time a construction which will present a pleasing appearance.

Another object of the invention is to provide a removable tooth construction capable of application to a bridge or crown.

A still further object of the invention is to provide a removable tooth which may be applied at any time on the upper or lower jaw.

In the accompanying drawing:

Figure 1 is a view showing a mouth with a removable tooth applied therein, the same embodying the invention.

Fig. 2 is a fragmentary sectional view through Fig. 1 on line 2—2.

Fig. 3 is an enlarged front view of a bridge and supporting plate embodying certain features of the invention.

Fig. 4 is an enlarged rear view of the tooth as adapted to be applied to the plate shown in Fig. 3.

Fig. 5 is a sectional view through Fig. 4 on line 5—5.

Fig. 6 is a sectional view through a single tooth showing an embodiment of the invention applied to a crown.

Referring to the accompanying drawing by numerals, 1 indicates a bridge of any usual or preferred construction, the same being shown as a comparatively narrow strip of metal fastened in a suitable manner to adjacent teeth in such a manner that the removable tooth 2 may be arranged therebetween and present a structure which will appear substantially the same as a natural tooth.

In Figs. 3 to 5 inclusive will be seen details of the tooth, which include a supporting plate 3, soldered or otherwise secured to the bridge 1, said plate being provided with a snap head or stud 4 and a projection or pin 5. The stud 4 is designed to snap into a socket 6 in the tooth 2, which is made from porcelain, or any other desired material. A depression or slot is also formed in

the tooth 2 for accommodating the pin 5 whereby the tooth cannot rotate. The socket member 6 is, of course, embedded into the tooth 2 when the same is being formed so that when it is desired to apply the tooth 2 the same may be moved flatwise against the plate 3 and the socket 6 forced over the stud or head 4 while the pin 5 moves freely into the slot 7. The tooth 2 is of exactly the same size as plate 3 or slightly larger so as to be properly supported and backed up by this plate without the plate being seen.

In Fig. 6 will be seen a slightly modified form of the invention, in which the tooth 2' is connected to a supporting plate 3', which supporting plate is soldered or otherwise secured to a crown 8 fitted in any desired or usual manner upon the rear section 9 of the tooth 10. In this form of the invention the tooth 10 must be cut away somewhat to accommodate the removable tooth 2'. In forming the tooth 2' of porcelain the gold is not seen, or at least a very small part of the gold is seen, consequently the tooth will present substantially the usual appearance of natural teeth, and when arranged as shown in Fig. 6 will act also as a natural tooth when masticating food.

The structure shown in Figs. 3 to 4 will also act as means for biting or masticating food, but is not quite as strong as the structure shown in Fig. 6, as the bridge is made very narrow in order to produce a nice appearance.

What I claim is:

1. A removable tooth comprising a tooth structure, a supporting plate, and means for connecting the tooth structure with the plate so that the tooth structure will not move independently of the plate, said means including a snap fastener.

2. A removable tooth of the character described comprising a supporting plate, a pin extending from said plate, a tooth member having an opening for receiving said pin, and a snap fastener spaced from said pin for connecting the tooth member with the plate, said pin acting as means for preventing rotary movement of the tooth member when secured to the plate.

3. A removable tooth comprising a tooth member provided with a metallic socket and a pin adjacent said socket, a base plate for receiving said tooth member, a pin extending from said base plate adapted to fit in said opening, and a resilient stud arranged

adjacent said pin for fitting into said socket for removably connecting the tooth member with the base plate.

4. A removable tooth comprising a base plate adapted to be supported by the teeth, said base plate being formed of metal, a pin extending from said base plate, a stud extending from said base plate, a porcelain tooth adapted to fit flatwise against said base plate, said tooth having an opening for receiving said pin, and a metallic socket member embedded in the rear of said tooth for snapping over said stud.
5. A removable tooth, comprising a removable tooth body, a backing adapted to be connected to one or more natural teeth,

and means presenting a snap fastener for connecting said tooth body with said backing.

6. A removable tooth, comprising a removable tooth body, a permanently fixed backing conforming to the shape in outline of a tooth and to said removable tooth, means for connecting said removable tooth with said backing, said means comprising a socket, a resilient stud adapted to snap into said socket for holding the removable tooth body in place, and means for preventing rotary movement of the tooth body around said stud.

CLAUDE ASTOLFO CONOVER.
